PLAYING CARD CABINET

Julius Bandes and Joseph Bandes,
Brooklyn, N. Y.

Application March 30, 1932, Serial No. 601,924

4 Claims. (Cl. 273—148)

This invention relates to a novelty container and receptacle for playing cards and for a playing card game.

It is an object of our invention to provide a receptacle to retain playing cards which may be converted in a simple manner to one which conveniently serves to facilitate the removal of a card or cards from stacks thereof, as where playing certain games with cards, in which a single card is removed from a stack. It is further contemplated by our invention to provide a container for one or more decks of cards, which substantially encloses such deck or decks, and which includes, in association with the container, of means to conveniently and quickly remove the decks without danger of breaking or folding any of the cards. Thus, it is contemplated by our invention to provide a container for decks of cards which is exceedingly compact, yet which is readily available for removing the contents thereof.

It is a further object of our invention to provide a container of minimum size for retaining a plurality of decks of cards which may be retained loose in the container, and which includes mechanism for facilely removing the contents, or which may be readily converted to retain the cards against accidental spilling of the contents when the lid or cover member for the container may be open in a position which would normally discharge or permit the cards to fall from the container.

It is a still further object of our invention to provide a container in the nature of a box to retain a plurality of decks of playing cards, the container being of minimum dimensions to retain the cards, the container including mechanism which will grip or clamp loosely stacked cards within the container against accidental spilling, and also coordinately serving as convenient means for removing the stacks of cards quickly and facilely without any danger of breaking or folding the individual playing cards.

To attain these objects and such further objects as may appear herein or be hereinafter pointed out, I make reference to the accompanying drawing forming a part hereof, in which—

Figure 1 is a perspective view of one embodiment of our invention;

Figure 2 is a section taken on the line 2—2 of Figure 1;

Figure 3 is a plan view detail of another embodiment of our invention;

Figure 4 is an enlarged fragmentary section taken on the line 4—4 of Figure 3;

Figure 5 is an enlarged fragmentary section taken on the line 5—5 of Figure 4;

Figure 6 is a perspective view of a still further embodiment of our invention;

Figure 7 is a side elevation of a still further embodiment of our invention;

Figure 8 is a plan view of a blank sheet used in making the embodiment illustrated in Figure 7.

Referring to the drawing, we have shown a box-like member 10 having a cover or leaf 11 hingedly connected therewith to form a closure for the container, by the hinges 12. This container may be mounted upon legs 13 to enhance the appearance of the container. The side walls 14 and end walls 15, in association with the bottom 16, are arranged in dimensions to substantially snugly contain two or more decks of playing cards 17. Disposed within the container, we provide a tray member 18 of substantially the same size as the interior dimensions of the box, and this member is provided with an upstanding partition 19 at substantially the medial point. The partition is extended beyond the upper edges of the walls 14 and 15 to provide a handle or finger gripping section 20.

By the construction as provided, two stacks of decks of cards 17 and 17a may be superimposed upon the tray member 18. In this position, the side walls and end walls 14 and 15 respectively, cooperate with the partition 19 to prevent displacement of the cards from one stack into another, or from the interior of the container, when the lid is moved to the open position.

For purposes of playing certain games where it is desired to deal a single card at a time, the tray member is tilted in the position shown in Figure 1, having one end of the tray resting upon the side wall 14, the opposite end resting upon the bottom 16. To assure this position, the bottom member 16 may be provided with a series of serrations or notches 21. In this position, individual stacks of cards are substantially confined against displacement from one portion of the tray to another, and a single card may then be removed from the top of the deck, in accordance with the playing rules of the game.

By the construction as provided, after the initial deck has been broken and stacked between the partition, the two decks may be bodily removed quickly and facilely, which will be apparent, particularly where the container is formed of minimum size to just retain two decks of cards with very little clearance space between the outlines of the decks and the side and end walls of the container.

In a still further embodiment of our invention, as especially illustrated in Figures 1 and 2, the partition member 18 is formed adjacent the upper medial portion with a drill hole 22. This 5 drill hole 22 is positioned in the partition 19 at a point usually occupied by the uppermost card of a complete deck. Through the drill hole 22 there is then passed a retaining bar or stick 23, 10 preferably in this particular case, a pencil. This 15 positioning of the cross element or pencil serves to bind the stacks of cards against the tray member 18, so that the tray and contents may be removed bodily without accidental spilling of the 20 contents, in addition to performing the novel 25 functions heretofore attributed to the tray member. The positioning of the pencil in the cross-wise direction as indicated, not only serves as a convenient receptacle for holding the pencil where this member is used, but also prevents the 30 spilling of the cards should the container be inverted. This will prevent cards belonging to the individual decks becoming mixed with cards of the other deck.

In a still further embodiment of our invention, 25 as particularly illustrated in Figures 3, 4 and 5, a tray member 18a of a size suitable to be retained within the container 10, as in the prior embodiment, is formed with a partition element 19a, in general contour corresponding to the partition element 19 of the embodiment already referred to. The partition member 19a is formed at its medial point adjacent the upper edge 20a with an elongated opening 21a. Along the edge 20a, the partition is slotted as shown at 22a, the 30 slotting being sufficiently deep to intersect the major portion of the opening 21a. Adjacent one edge of the wall of the slotted portion 22a there is inserted a spring wire or leaf 23a. This wire is anchored on one end 24a into the bottom wall of the slotted portion 22a, and where the partition 19 is made of wood, this may be accomplished by 35 driving this end of the spring into the wood of which it is formed. The spring member 23a is bent so that it will normally bear down towards the bottom of the slot 22a. For lifting the spring 23a from this position, there is provided a vertical section 25a of substantially the same length as the depth of the slot 22a. The extreme end is formed with a finger engaging offset member 26a.

By the construction just described, a tray member such as completely illustrated in Figure 3 may serve to hold on opposite sides thereof, separated by the partition 19a, two decks or stacks of cards. With this stacked in this loose position, the contents may be conveniently inserted 50 within the confines of the container 10. When so positioned, a cross element or pencil 23 may be inserted in the opening 21a, first preferably lifting the spring 23a upwardly. Upon release of the spring this member will serve to press down 55 upon the cross member or pencil 23. The action will be as previously described, especially where the cards are present to grip the same and prevent accidental displacement, as when lifting the tray member and contents from the container 10, or 60 when the container and contents, when closed, may be inverted.

In Figure 6, we have illustrated a still further embodiment of our invention, especially as to 65 that portion which may constitute the tray member. In this embodiment, a tray 18b is of a size and contour corresponding substantially to the section 18 of the tray already referred to, so that it may snugly fit upon the bottom 16 of the 70 container 10. Vertically disposed upon the me-

dial portion, we provide a wire partitioning member 19b. This is preferably of spring wire and formed as an inverted loop in which the arms 20b have their ends 21b driven through the tray at the medial point to hold the wire vertical in relation to the tray 18b. At the central section of the loop of the member 19b, there is formed a downwardly turned arm 22b and the central portion is reversely looped at 23b. By this construction a wire loop 19b serves as a partitioning member in association with the tray 18b, and further when this tray, as thus described, has positioned thereon to opposite sides of the partition 19b, a pair of decks of cards, a cross member or pencil 23 may be slipped under the loop 23b. 15 The loop is formed so that it will be disposed below the height of a deck of cards. The resilient pressure exerted by the wire or ribbon of which the partition 19b is formed will serve to press the cross member or pencil down upon the decks of cards to prevent displacement thereof. 20

In Figures 7 and 8 we have illustrated a still further embodiment of our invention, which comprises an assembly which may be used instead 25 of any one of the tray members described in the previous embodiment. This detail comprises a score pad 24 having a relatively rigid back 25, such as may be obtained in using pasteboard or cardboard. To one end 26 of the pasteboard 30, there is affixed a leaf or cover 27 made of heavy paper. This may be affixed to the score pad by adhesive 28 or similar securing means. The cover 27 described is made from a blank as shown in Figure 8, and this is formed with score 35 lines 28 and 29 to form the corners 28a and 29a and score lines 30 and 31 serving to form the partition 19c. The score line 31 is positioned substantially the medial portion of the blank sheet, transversely thereof, in order to position the partition 19c at substantially the central portion of the score pad. The construction described, when ready for use, is first inserted within the container 10, leaving the partition formed by the cover 27 at 19c substantially vertically disposed. 40 Two decks of cards 17 and 17a may then be superimposed upon the score pad in the construction just described, the position of the partition 19c being disposed for a length higher than the thickness of a deck of cards. By this construction, the score pad forms a convenient tray for the decks of cards in accordance with the embodiments previously described, the decks of cards being maintained within the confining walls of the container itself and the partition 19c holding the cards when loosely stacked to prevent 45 intermixing of the cards. To remove the decks from the container, the partition 19c may be grasped and pulled upwardly, bringing the cards to a position where they may be readily removed from the container. By our invention as described in the various embodiments, it will be observed that we have provided a container and partitioning tray member in which stacks of cards may be conveniently packed and occupy 50 the minimum space for at least two decks of cards, so that they may lie flat in the container, loosely, without any intermixing of the cards, and that though the confining walls of the container snugly engage the cards, they may be removed 55 facilely by bodily lifting the tray. Furthermore, by the embodiment just shown and illustrated in Figure 1, the tray may be utilized as a convenient method of stacking a deck of cards in a tilted position, where it is desired to use the 75

cards in the playing of games in which one card or more is removed at a time without handling the entire deck, one section partitioned by the tray thus formed being available for undisclosed cards, the other for disclosed cards, or both may be used for undisclosed cards, in accordance with the game that is being played with the cards.

It will further be observed in other embodiments of our invention, that the construction permits of the features above described, and in addition, particularly where the card holding means is associated with the partition, the cards are maintained in a container in an orderly fashion in all positions of the container when it is closed, and holds the cards against accidental spilling when the container is open, or serves to assure that the contents of the container may be bodily removed facilely, even though the materials stacked therein are loosely associated.

Having thus described my invention and illustrated its use what I claim as new and desire to secure by Letters Patent, is—

1. In a playing card cabinet of the character described, comprising a main bottom member and a lid therefor, the bottom member being arranged to hold a pair of stacked cards snugly in side by side relation, a removable tray including a partitioning member upon which said independent stacks are arranged to be disposed, said tray and partitioning member cooperating with the confining walls of said bottom member to hold said stacks segregated, said partitioning member of said tray being extended beyond the normal depth of a stack of playing cards to permit facile removal or positioning thereof bodily to a tilted position on one of the side walls of the bottom member, a cross member arranged to be disposed over said cards, and means formed on said partitioning member for removably holding said cross member over stacked decks of cards to either side of said partitioning member, said ex-

tended portion of said partition serving as engaging means for removal of the tray and mounting for said cross member.

2. In a playing card cabinet of the character described, a bottom member and closure therefor, said bottom member being of a size to snugly hold a pair of decks of cards in stacked relationship, a removable tray, a partitioning member medially disposed and connected to said tray co-operating with the side walls of said bottom member to hold said decks segregated in stacked relationship, a finger engaging extension on said partition and means formed in the bottom member to hold said tray tilted upon the side wall of said bottom member.

3. In a playing card cabinet of the character described, a bottom member and closure therefor, a removable tray arranged to lie over said bottom member, comprising a score card including a cover member, score lines formed in said cover member for folding said cover member medially into a partitioning fold whereby a pair of decks of cards may be stacked upon said score card and be held in segregated stacked relationship, said folded cover of said score card being extended to form a finger engaging portion whereby the score card and stacked cards may be bodily removed.

4. In a playing card cabinet of the character described, a bottom member and closure therefor, a tray formed in said bottom member including a partitioning member formed of looped wire, a reflexly formed loop at the medial portion of said partitioning member, said reflexly formed loop including a central fold arranged to engage a cross member and resiliently urge the same against stacked decks of cards to either side of said partitioning member.

JULIUS BANDES.
